CLAIM

We claim the ornamental design for the sofa, as shown and described.

DESCRIPTION

FIG. 1 is a top, perspective view of a sofa comprising the present invention.

FIG. 2 is a front elevational view of the sofa shown in FIG. 1.

FIG. 3 is a side elevational view of the sofa shown in FIGS. 1 and 2.

FIG. 4 is a side elevational view of the sofa shown in FIGS. 1, 2, and 3.

FIG. 5 is a rear elevational view of the sofa shown in FIGS. 1, 2, 3, and 4.

FIG. 6 is a top plan view of the sofa shown in FIGS. 1, 2, 3, 4, and 5; and,

FIG. 7 is a bottom plan view of the sofa shown in FIGS. 1, 2, 3, 4, 5, and 6.

The broken lines are for environmental purposes only and form no part of the claimed design.
